Related U.S. Application Data

CLAIM

(63) Continuation of application No. 29/424,254, filed on Jun. 8, 2012, now Pat. No. Des. 710,382.

The ornamental design for a display screen or portion thereof with graphical user interface, as shown and described.

(51) **LOC (10) Cl.** **14-04**
(52) **U.S. Cl.**

DESCRIPTION

USPC **D14/487**

The patent or application file contains at least one drawing executed in color. Copies of this patent or patent application publication with color drawing(s) will be provided by the Office upon request and payment of the necessary fee.

(58) **Field of Classification Search**

FIG. 1 is a front view of a display screen or portion thereof with a graphical user interface showing my new design; FIG. 2 is a front view of another embodiment of a display screen or portion thereof with a graphical user interface showing my new design;

USPC ..... D14/485—495
CPC G06F 3/0482; G06F 3/04842; G06F 3/04817; G06F 3/048; G06F 17/211; G06F 17/212

FIG. 3 is a front view of another embodiment of a display screen or portion thereof with a graphical user interface showing my new design; and,

See application file for complete search history.

FIG. 4 is a front view of another embodiment of a display screen or portion thereof with a graphical user interface showing my new design.

(56) **References Cited**

The broken lines around the Figures show a display screen or portion thereof and form no part of the claimed design.
